UNITED STATES PATENT OFFICE.

MARTIN A. JANES, OF NORTHFIELD, MASSACHUSETTS.

SWITCHBOARD-PLUG.

1,104,195.

Specification of Letters Patent. Patented July 21, 1914.

Application filed November 13, 1913. Serial No. 800,730.

To all whom it may concern:

Be it known that I, MARTIN A. JANES, a citizen of the United States, residing at Northfield, in the county of Franklin and State of Massachusetts, have invented a new and useful Switchboard-Plug; and I do hereby declare the following to be a full, clear, and exact description of the invention, such as will enable others skilled in the art to which it appertains to make and use the same.

This invention relates to a new and useful improved switchboard plug.

Heretofore in removing and replacing the braided cord (which incases the conductor wires), it necessitates great care, time and patience in accomplishing the same, owing to the fact that the cord has to be twisted into and out of the threaded head or collar of the plug. This will, in some instances, disarrange the terminals (which are soldered or otherwise secured to the wires.) Furthermore, the threads will tend to cut the braided casing, and in this way the braided cord will become considerably worn.

The object of the present invention is to obviate these above features and disadvantages, by providing a two part plug head, one of the parts forming an integral connection with the plug, while the other part is detachable and constitutes a clamp. In attaching the braided cord to this form of plug head, the cap or clamping part is first removed, then the braided cord is placed in the other part, after which the clamping part or cap is replaced, there being screws passing through ears of the clamping part, for holding the same to the other part. The two parts of the head are provided with pointed spurs or teats upon their inner surface to embed in the braided cord, to prevent the same from slipping.

One of the features of the invention is the provision of a tongue and groove connection between the two parts, to hold the two parts in registration, while the screws are being turned home.

In practical fields the details of construction may be subject to alterations, falling within the scope of what is claimed.

The invention comprises further features and combination of parts, as hereinafter set forth, shown in the drawings and claimed.

In the drawings: Figure 1 is a view in perspective of a switchboard plug constructed in accordance with the invention. Fig. 2 is

a longitudinal sectional view on line 2—2 of Fig. 1. Fig. 3 is a transverse sectional view on line 3—3 of Fig. 1. Fig. 4 is a detail view showing the two parts of the head 60 separated.

Referring more particularly to the drawings, 1 designates the usual form of switchboard plug, with the exception that the head 2 of the plug comprises two parts 3 and 4, 65 the part 3 having an integral connection as at 5 with the plug proper. The part 3 upon each side is provided with a recess 6, and a tongue 7 and shoulder 8. The part or clamp or cap 4 is provided with ears 9 upon the opposite longitudinal edges, which ears are received by the recesses 6, secured in place by the small screws 10. The opposite longitudinal edges of the clamping cap or part 4 are provided with grooves 11 to receive the tongues 7, and supplied with tongues 12 to engage the shoulders 8 of the part 3. These tongue and groove and shoulder connections acting to hold the two parts in registration while the screws are being 80 turned home.

The part 3 of the head upon its inner circumference is provided with a series of pointed spurs, lugs or teats 13, while the clamping cap or part 4 is constructed with pointed spurs or teats 14, these teats 13 and 14 acting to prevent the braided cord from slipping. The points of the teats are not extremely sharp, but are slightly rounded, as shown, so as to not cut, mar or disfigure the 90 cord.

From the foregoing in conjunction with the annexed drawing, it will be noted that there has been devised a simple and effective and efficient two part head for a switchboard plug, and one which has been found practical, in view of the fact that it obviates the necessity of great care, time and patience in attaching and detaching the braided cord to the plug.

The invention having been set forth, what is claimed as new and useful is:

In combination with a switchboard plug, a head comprising two separable parts, one being integral with the plug and having recesses upon its longitudinal edges, said longitudinal edges having tongues and shoulders adjoining said recesses, the other parts being detachably connected to said integrally connected parts and having ears to engage said recesses, said parts being semi-cylindrical, and the recesses and ears conform-

ing to the cylindrical contour of said parts, means passing through the ears for detachably fastening said parts together, the detachable part having its longitudinal edges provided with longitudinal shoulders and tongues corresponding to and adapted to cooperate with the first shoulders and tongues so as to insure the detachable parts against slipping, said parts upon their inner cylin-

drical surfaces having a plurality of spurs 10 to prevent the cord from slipping.

In testimony whereof I have signed my name to this specification in the presence of two subscribing witnesses.

MARTIN A. JANES.
